UNITED STATES PATENT OFFICE.

ELLIS W. COOPER, OF BLOOMFIELD, NEW JERSEY, ASSIGNOR TO R. HOE AND CO., OF NEW YORK, N. Y., A CORPORATION OF NEW YORK.

SHEET-DELIVERY MECHANISM.

1,160,854.

Specification of Letters Patent. Patented Nov. 16, 1915.

Application filed July 29, 1913. Serial No. 781,775.

To all whom it may concern:

Be it known that I, ELLIS W. COOPER, a citizen of the United States, residing at Bloomfield, county of Essex, and State of New Jersey, have invented certain new and useful Improvements in Sheet-Delivery Mechanism, fully described and represented in the following specification and the accompanying drawings, forming a part of 10 the same.

This invention relates to certain improvements in sheet-delivery mechanism, and has been designed for use especially with printing machines, but, if desired, may be used 15 in other relations.

In printing certain classes of products, as, for instance, magazines, during the greater part of the time the product will be of a common variety which can stand 20 handling, but at times in such printing it is desirable to produce a product of higher grade which should be handled during the delivery operation as little as possible. When work of the ordinary variety is being produced, the delivery may be and preferably is a continuous one, but when a higher grade product is being produced, to avoid handling the product is delivered 25 in bunches, each bunch having a predetermined number of the products. In this latter or bunch delivery the products are delivered generally to a traveling carrier having a series of partitions or pockets, the carrier being operated intermittently to move 30 forward a pocket length when a pocket has received a predetermined number of products.

It is an object of the invention to produce a delivery which may be operated 40 either to deliver the products, as printed sheets, continuously, or to deliver such products in bunches or bundles having a predetermined number.

It is a further object of the invention to 45 provide a carrier of improved construction which may be employed either for the continuous delivery or bunch delivery, as desired.

For a full understanding of the invention, a detailed description of mechanism embodying the same will now be given in connection with the accompanying drawings, in which—

Figure 1 is a side elevation, partly in sec-

tion, with certain parts broken away to 55 show the construction of a part of the improved delivery mechanism, the part shown being adapted to deliver the products in bunches, each bunch having a predetermined number. Fig. 2 is a side elevation, partly in 60 section and partly broken away, of a portion of the improved delivery, the part shown being arranged for delivering the product continuously, the view being taken on the side of the machine opposite to that 65 shown in Fig. 1; Fig. 3 is a plan view of the improved delivery device, showing the construction illustrated in Figs. 1 and 2; Figs. 4, 5 and 6 are detail views on an enlarged scale of the improved carrier construction employed whereby the carrier 70 may be operated to deliver the product either continuously or in bunches.

Referring now to the drawings, the invention has been shown in connection with 75 a delivery cylinder 1 of a printing machine, though it will be understood that the invention may be used in other relations, and that products from other sources than the delivery cylinder of a printing machine 80 may be delivered by the improved mechanism. This delivery cylinder is of any usual or suitable construction and has coöperating therewith the usual stripper 2.

In accordance with the invention, a delivery mechanism is provided whereby the products may be delivered from the delivery cylinder either in bunches, each bunch having a certain predetermined number, or 85 continuously. The particular mechanism 90 for effecting this may be widely varied. In the best constructions, and as illustrated, the delivery will include a traveling carrier with mechanism for driving this carrier intermittently or continuously, as desired, the carrier being so constructed as to 95 permit the products to be taken thereby either in bunches or continuously. The particular construction of this carrier may vary widely. As illustrated, it includes a 100 plurality of endless tapes 3. These tapes are supported in any suitable manner. In the particular construction illustrated, the tapes are carried on cross-bars or rods 4, these rods being secured to a pair of chains 105 5 which are driven in any suitable manner, as by sprockets 6, 7 carried respectively on cross-shafts 8, 9 suitably journaled in the

frame of the machine. Additional supports 10 may be provided if desired to prevent the bars and tapes from sagging, these supports being in the form of bars which are supported by suitable braces 11 on the frame of the machine, and a further center support 13 may be provided, if desired.

In order that the carrier may operate to deliver the products in bunches, each bunch having a predetermined number, the carrier is provided with instrumentalities forming recesses or pockets into which the products are delivered from the delivery cylinder, the carrier being intermittently moved ahead a pocket length by mechanism hereinafter described, when the desired number of products have been delivered to a pocket. The particular means employed for forming the pockets may be varied, but these means will be of such character that they can be withdrawn from the path of the sheets as they are delivered from the delivery cylinder, when it is desired to operate the carrier to deliver products continuously. In the construction illustrated, these pockets are formed by providing pins or fingers 14 suitably secured to the carrier, these fingers being spaced apart longitudinally of the carrier a sufficient distance to form pockets of the required dimensions. When these pocket forming devices are pins or fingers they are preferably carried on the rods 4, before referred to, which are mounted so as to be rotatable in suitable bearings so that the rods may be turned to cause the pins to assume a position parallel with and below the run of the tapes, as shown in Fig. 5, when it is desired to operate the carrier continuously. The particular construction for mounting the rods may be varied, but as shown each rod is provided with collars 15, 16 located beyond or outside the tapes, between which collars seats a spring 17. The collar 16 is provided with a projection or nose 18 arranged to take into either one of two notches 19, 20 formed in the journal or hub 21 carried by the chain and through which the rod at one end is secured to the chains. The rod at its other end is mounted in a suitable journal or hub 21' carried by the other chain, and the belts are secured on the rods in any suitable manner as by brackets 22, the rods being rotatable in the brackets. Through the tension of the spring 17 the rod is held firmly in the bearing 21 with the pin in upright position, when the nose 18 is in engagement with the notch 19. When it is desired to have the pins turned down out of the path of the product, the pin is grasped and pulled outwardly, or to the left, as shown in Fig. 4, which causes the nose 18 to become disengaged from the notch 19 with which it was in engagement. The pin is then turned down, the rod rotating in its bearings until the nose 18 engages

with the notch 20, the pin then being in the position shown in Fig. 5 and out of the way of the product as they are delivered onto the tapes, and the pins are held firmly in such position.

In accordance with the invention, connections are provided for driving the carrier either intermittently, to deliver the product in bunches, or substantially continuously, to effect a continuous delivery of the product.

Referring first to the means employed for effecting an intermittent or periodic movement of the carrier, these means will be preferably such as to give the carrier, when it is moved, a very quick movement, or jump, so that the carrier will be moved a pocket length with sufficient speed, after a pocket has been filled, to permit that pocket to be moved out of the way and the next pocket moved into position in time to catch the next product delivered from the delivery cylinder. The means for moving the carrier will also preferably, in the best constructions, form in effect a counting means, these means operating to move the carrier after a predetermined number of products have been delivered to a pocket. While the particular construction for effecting this result may be varied, as illustrated there is provided a power shaft 25 which, through a train of gears 25', 26, 27, 28, drives a short shaft 29 on which there is secured an arm 30 having a pin 31. This pin is adapted to engage with recesses 32 in a recessed or star wheel 33 suitably mounted on a stud 34 in the frame of the machine. Fast on the stud 34 is a cam 35 (see Fig. 3) having a cam groove 36 in which is mounted to run a cam roll 37 carried on an arm 38, pivoted at 39 in a suitable bracket on the frame of the machine. The other end of this arm is provided with a cam roll 40 which works in a grooved collar 41 on a shaft 42 suitably journaled in the frame of the machine. Keyed on the shaft 42, so as to slide thereon, is a second recessed or star wheel 43 provided with recesses 44 with which is adapted to engage the pin 31 before referred to, the wheel 43 being turned by this pin. The shaft 42, which is turned by the star wheel 43, is provided with a gear 45 which is in mesh with a gear 46 slidably mounted on the chain sprocket shaft 8, before referred to.

Through the construction illustrated, the arm 38 is operated to slide the star wheel into position to be engaged by the pin 31 once for every complete revolution of the star wheel 33, and for each revolution of the star wheel 33 the star wheel 43 is given a quarter turn. An intermittent drive is thus provided for the carrier, the carrier being moved forward at each quarter turn of the star wheel 43 a pocket distance after the pocket has had delivered to it the predeter-

mined number of products. This movement is further a very quick one, and permits of the proper operation of the carrier.

The means whereby the carrier may be driven continuously to effect a continuous delivery of the product will now be described. Preliminarily, it may be stated that when it is desired to operate the carrier continuously the pins or fingers 14, before referred to, are placed in their recumbent position out of the path of the products, and the connections for driving the carrier intermittently just described are thrown out of operation, this being conveniently accomplished by making the gear 25' on the power shaft 25 a sliding gear and unmeshing it from gear 26 by sliding it along the shaft, and also unmeshing gear 46 from gear 42. The particular mechanism employed for effecting the continuous movement of the carrier may be varied somewhat in construction. As illustrated, this mechanism is positioned on the other side of the machine, and, for compactness and simplicity of operation, is operated from power shaft 25, before referred to. In the particular construction illustrated, the end of the sprocket shaft 8 on the other side of the machine is provided with a ratchet 48 fast on the shaft with which coöperates a pawl 49 pivoted on a pawl arm 50 pivotally mounted on the shaft 8. This arm is operated to move the carrier substantially continuously by means of an eccentric 51 on power shaft 25 and eccentric rod 52 connected to the eccentric and the pawl arm 50. When it is desired to discontinue the means for driving the shaft just described for operating the carrier substantially continuously the pawl is, by means of a handle 53, lifted up out of engagement with the ratchet and the pawl arm simply runs free on the shaft.

While the invention has been shown and described as used in connection with the delivery cylinder of a printing machine, it will be understood that it may be used in other relations for delivering products from various sources of supply, and that it is not to be limited to use in conjunction with a printing machine nor to the particular construction or arrangement of the parts described, but that changes and variations may be made in the same without departing from the invention.

55 What is claimed is:

1. In a delivery device, the combination with a traveling carrier having sheet receiving pockets, of mechanism for giving the carrier an intermittent forward movement after a predetermined number of

sheets have been deposited in a pocket, mechanism for giving the carrier a continuous forward movement whereby the sheets are delivered continuously, connections whereby either mechanism may be thrown into operative relation with respect to the carrier, and means whereby the pockets on the carrier may be thrown out of sheet receiving position.

2. In a delivery mechanism, the combination with a traveling carrier having fingers forming a plurality of sheet receiving pockets, means for giving the carrier an intermittent forward movement after a predetermined number of sheets have been delivered to a pocket, means for giving the carrier a continuous forward movement for delivering a product continuously, connections whereby either mechanism may be brought into operative relation with the carrier, and means whereby the pocket forming fingers on the carrier may be retracted from the path of the product.

3. In a delivery mechanism, the combination with a traveling carrier, of a shaft for driving the carrier, mechanism connected with one end of the shaft for giving the carrier an intermittent traveling movement to effect the delivery of a product in bunches of predetermined numbers, mechanism connected with the other end of the shaft for giving the carrier a continuous traveling movement to effect a continuous delivery of the product, and connections whereby either mechanism may be thrown into operative relation with the carrier.

4. In a sheet delivering mechanism, a carrier comprising a plurality of traveling tapes, chains for driving the tapes, a plurality of rods rotatably mounted in the carrier, said rods being spaced apart, and fingers carried by said rods and rotatable therewith to raised position to form sheet-receiving pockets and to lowered position to retract them from sheet-receiving position.

5. In a sheet delivery mechanism, a flexible traveling carrier and means for driving it, a plurality of rods rotatably mounted in the carrier and spaced apart, and fingers carried by said rods and rotatable therewith to form when in raised position sheet-receiving pockets and when lowered to extend below the surface of the carrier.

In testimony whereof, I have hereunto set my hand, in the presence of two subscribing witnesses.
